UNITED STATES PATENT OFFICE.

DANIEL J. CLARK, OF JERSEY CITY, NEW JERSEY, ASSIGNOR TO
HILLIARY ELDRIDGE AND JAMES C. YOUNG, OF JERSEY CITY,
NEW JERSEY.

INCANDESCENT MANTLE.

No. 807,060.

Specification of Letters Patent.

Patented Dec. 12, 1905.

Application filed June 14, 1905. Serial No. 265,152.

To all whom it may concern:

Be it known that I, DANIEL J. CLARK, a citizen of the United States, and a resident of Jersey City, in the county of Hudson and State 5 of New Jersey, have invented certain new and useful Improvements in Incandescent Mantles of which the following is a specification.

My invention relates to incandescent mantles.

10 It has for its object to provide an incandescent mantle comprising a plurality of hollow sections placed together to form a ring, whereby the illuminating-surface of a single mantle is increased, and if one of the sections 15 becomes burned out or broken it may be removed and replaced by a new section, thus effecting a great saving of the mantles.

It has for a further object to provide a mantle of the character set forth embodying 20 advantages in point of simplicity and inexpensiveness of construction, attractiveness, and effectiveness in use.

In the drawings, Figure 1 is a sectional view showing my mantle supported on a 25 burner. Fig. 2 is a perspective view of the mantle. Fig. 3 is a perspective view of a modified form of the mantle.

In all the figures of the drawings illustrating my invention like reference characters 30 designate corresponding parts.

Referring to Figs. 1 and 2 of the drawings, 1 designates a burner-head connected with the gas-supply by a pipe 2 and comprising a casting embodying a central chamber 3, a reticulated cap 4 therein, and downwardly-extending radiating burners 5, leading from the chamber 3. To provide means for supporting a mantle-hanger and mantle, to be hereinafter described, in the proper relation to the burners, bosses 6 are formed on the burners, and each is provided with a vertical bore 7, intersected by horizontal screw-threaded bore 8, engaged by a set-screw 9. A globe 10, open at the top and closed at the bottom, is supported on the supply-pipe, so as to surround the burner, mantle, and hanger.

The hanger employed for supporting the mantle comprises independent frames 25 and

26, each formed of a single piece of wire bent to present a horizontal portion 27, having 50 large openings connected by narrow passages and a vertically-extending portion 28, adapted to be inserted into one of the bores 7 in the burner and be secured therein by the set-screw 9. 55

The incandescent mantle, which is supported on the hanger above described, comprises independent hollow curved sections 30 and 31, substantially U-shaped in cross-section and having pockets 32, 33, and 34, into 60 which the burners project, connected by narrow passages 35 and 36. By this arrangement each flame of the burner will be partially confined within a pocket of the mantle.

Referring now to the modification shown 65 by Fig. 3 of the drawings, this form of mantle comprises a plurality of hollow independent substantially semicircular sections 40 and 41. The hanger 50 for supporting this form of mantle comprises independent substantially semicircular frames 42 and 43, having vertically-extending portions 43'. 70

These hangers are not herein claimed, as they form the subject of an application which I have filed concurrently herewith. 75

I do not wish to be understood as limiting myself to the precise details and arrangements of parts shown and described, but reserve the right to all modifications within the scope of my invention. 80

Having now described my invention, what I claim as new, and desire to secure by Letters Patent, is—

1. An incandescent mantle consisting of a plurality of independent hollow sections 85 enclosing a space therebetween, substantially as described.

2. An incandescent mantle consisting of a plurality of independent hollow sections 90 enclosing a space therebetween, each section having a plurality of pockets, substantially as described.

3. A ring-like incandescent mantle, comprising a plurality of independent curved hollow sections substantially U-shaped in 95 cross-section, substantially as described.

4. A ring-like incandescent mantle, comprising a plurality of independent curved hollow sections, each having a plurality of communicating pockets, substantially as described.

5. A ring-like incandescent mantle, comprising a plurality of independent curved hollow sections substantially U-shaped in cross-section and having a plurality of com-

municating pockets, substantially as described.

Signed at New York, in the county of New York and State of New York, this 15th day of May, A. D. 1905.

DANIEL J. CLARK.
